MANUAL ADAPTER FOR AUTOMATIC CHOKES

Albert L. Coulter, Chicago, Ill.

Application February 1, 1950, Serial No. 141,776

2 Claims. (Cl. 137—484)

1

The present invention relates to a manual adapter for an automatic choke and more particularly to manual control means for replacing a thermostatic automatic choke control element for an internal combustion engine.

Several types of thermostatically-operated automatic choke controls for internal combustion engines, such as the conventional automobile engine, have been proposed and are commercially available. However, such controls are often unsatisfactory under certain weather conditions, such as in starting the engine in cold weather. The delayed response of the thermostatic control to engine operating conditions and the impossibility of independently controlling the richness of the fuel-air mixture fed to the combustion chamber of the engine are added disadvantages of such automatically operated choke controls.

The present invention now provides an adapter unit which may be readily installed on the carburetor of an automobile engine to replace an originally supplied thermostatically-controlled automatic choke control. The adapter of the present invention may be employed with various types of carburetors which are now commercially available, and a relatively small number of adapter types may serve to convert a large number of carburetor types to manual control.

In addition, the present invention provides a choke flutter control which prevents flooding of the engine with excessive fuel, even though the choke valve is manually closed. This flutter control preferably takes the form of means resiliently biasing the choke to closed position while accommodating opening movement of the choke valve to permit the passage of air through the carburetor to thin out an excessively rich fuel mixture fed to the engine under excessive manifold vacuums.

It is, therefore, an important object of the present invention to provide an improved manual choke adapter for thermostatic-type automatic choke control.

Another important object of the present invention is to provide an adapter unit for converting an automatic thermostatically-controlled choke to a manually controlled unit, thereby eliminating the undesirable characteristics of the thermostatically-controlled unit.

It is a further important object of the present invention to provide an improved manual choke control provided with a resilient flutter control for preventing flooding of an internal combustion engine with an excessively rich fuel mixture.

Still another important object of the present

10

invention is to provide an improved manual control for a carburetor choke valve for an internal combustion engine including resilient means biasing the choke valve to closed position while permitting opening of the choke valve by excessive manifold vacuum in the engine, thereby admitting air to the engine to preserve a desired fuel-air ratio in the combustion mixture fed to the engine.

in elevation, taken along the plane XVII—XVII of Figure 15; and

Figure 18 is a fragmentary sectional view similar to Figure 12 showing a modified form of actuating arm.

As shown on the drawings:

Reference numeral 10 refers generally to a carburetor of the type generally employed in automotive internal combustion engines. The carburetor 10 includes an upper air horn 11 having an interior air inlet passage 12 (Figures 2 and 3), a central fuel mixing portion 13 and a lower outlet portion 14 having a lower terminal flange 15 adapted for connection to the intake manifold of an engine.

The air inlet passage 12 is controlled by a choke butterfly valve 16 mounted on a rotatable actuating shaft 17 extending radially across the passage 12 and secured to an upstanding bell crank arm 18 having an outturned terminal flange 19.

Inasmuch as the carburetor 10 is initially equipped with a thermostatically-controlled automatic choke, a generally cylindrical housing 20 is provided along the side of the air inlet horn 11, the housing surrounding the bell crank arm 18. The housing 20 is provided with a plurality of peripherally spaced radially extending bosses 21 normally employed to secure a housing cover on the housing 20, thereby confining a conventional coil spring-type thermostatic element therein for connection to the crank arm 18. Upon removal of the cover (not shown) and the removal of the thermostatic element (not shown), the housing 20 may be employed for the attachment of an adapter unit of the present invention.

In Figures 1-5, inclusive, reference numeral 22 refers generally to an adapter unit bracket including a base arm 23, a first angularly displaced arm 24, a web arm 25 parallel to the base arm 23, and a second angularly displaced arm 26 terminating in an outturned terminal arm 27. The bracket is secured by suitable means, as by screws 28 passing through registering apertures in the arms 24 and 27 and the bosses 21. It will be noted that the web arm 25 underlies the crank arm 18 in spaced relation thereto to permit pivoting movement of the crank arm through its entire operating arm (Figures 1 and 3).

The base arm 23 carries a cable bracket 29 projecting thereabove and secured thereto by suitable means, as by screws 30. The web arm 25 carries an arm 31 attaching thereto by means of a pivot pin or rivet 32. The arm 31 is provided with an aperture 33 for receiving the terminal end of the crank arm 18, and the arm 31 is longitudinally slotted, as at 34, at that end remote from the pivot pin 32. An additional projection 35, formed integrally with the arm 31 and apertured as at 36, extends normally to an intermediate portion of the arm 31 between the pivot pin 32 and the aperture 33. The crank arm terminal end 19 of various types of carburetors may be alternately received by either of the apertures 33 or 36.

The slot 34 of the arm 31 slidably journals a block 37 (Figures 4 and 5) provided with a projection 38 (Figure 2) extending into and bottomed within the slot. The block 37 is provided with a longitudinally extending, generally cylindrical housing 39 having a piston 39 journaled therein for reciprocating movement against the influence of a coil spring 40 confined between the piston and the housing. That end of the piston 39 projecting beyond the housing 39 is axially bored as at 41 to receive an actuating rod or wire 42 se-

cured in the piston by means of a set screw 43 threadedly retained by a screw block 44 for engagement with the rod 42. The actuating wire 42 is enclosed within a conventional flexible cable 5 housing 45 of the Bowden-type.

The operation of the hereinbefore described embodiment of the invention will be understood from reference to the drawings 1 and 3. When the choke control rod or wire 42 is in its normal inoperative position, the choke valve 16 is open and air flow through the air inlet horn 11 and the air inlet passage 12 is accommodated. Upon actuation of the rod 42, the valve 16 is gradually closed in accordance with movement of the rod 15 to the final full closed position as indicated in dotted outline in Figure 3 of the drawing, which occurs at the fully retracted position of the actuating arm 42. It will be noted that the closing movement of the valve is accommodated by pivoting movement of the arm 31 about the pivot stem or rivet 32. Thus, pivoting movement of the arm 31 causes corresponding movement of the crank arm 18 by reason of engagement of the arm with the terminal end 19 of the crank arm inserted 20 in the aperture 33. Little resistance is offered to this closing movement of the valve 16, particularly prior to the starting of the engine.

The flutter control is employed to vent the intake manifold of the engine to air when excessive vacuums are generated in the manifold to thereby prevent the feeding of excessive fuel to the manifold, and consequent flooding of the engine is likewise prevented. This flutter control is provided by the spring-urged piston 39 disposed within 30 the housing 38. The over-balanced valve 16 will be urged open under the differential pressure conditions set up upon the generation of excessive vacuums in the manifold with consequent pivoting movement of the valve 16 about its shank 35 40 17. This pivoting movement of the valve is accommodated by the spring 40 which is resiliently compressed upon movement of the housing 38 relative to the piston 39 to permit pivoting movement of the arm 31 to its dotted position in Figure 3 without corresponding movement of the actuating rod 42. In this manner, the valve 16 may be cracked or slightly opened to its dotted position 16a (Figure 3), while the actuating rod 42 remains in its full open position.

Another embodiment of the invention is illustrated in Figure 6 of the drawing wherein the device 22 has been modified by the addition of a separate link arm 46 to the terminal arm 27. The link arm 46 is secured to the terminal arm 55 27 by means of screw 47, while an additional screw 48 is employed to secure the link arm to a projection or boss 49 formed on the housing 20. This arrangement is employed in conjunction with those carburetors of such design that the apertures in the arms 23 and 27 do not register with the corresponding apertured embossments 21 of the housing 20. It will thus be appreciated that the arrangement of the bracket 22 and the apertures thereof, particularly when employed in conjunction with the additional arm 60 65 46, permit the adaption of the unit to a relatively large number of carburetors of varying design and overall shape.

A further embodiment of the invention is illustrated in Figures 7-10, inclusive, wherein a modified adapter unit is illustrated as employed with a slightly different form of carburetor. The reference numeral 50 refers generally to a carburetor in which the normally provided thermostatic choke control is vertically displaced from

the choke valve. More particularly, in the carburetor 50, a choke crank arm 51 is secured to an elongated choke actuating arm 52, which in turn was initially actuated by a thermostatic control. In the present invention, the actuating arm 52 is secured, as by a cotter pin 53, to a manual control arm 54 pivoted at 55 to an upturned bracket flange 56 carried by a generally horizontal bracket arm 57 which in turn is secured to a mounting flange 58 (Figure 8) on the carburetor 50 by suitable means, as by a screw 59 and a nut 60. The bracket 57 is in extended surface contact with the flange 58 and carries thereon an upstanding cable bracket 61 bearing a spiral-type cable housing 62 and an actuating wire 63 secured to the arm 54 by suitable means, as by an attaching stud 64.

A modified form of control arm 54 is shown in Figure 18, the arm 54 being provided with an enlarged free terminal end 54a having a plurality of arcuately aligned apertures 54b to permit the utilization of various lengths of actuating arm 52, thus adapting the arm 54 for use with several types of carburetors.

In Figures 8, 10 and 11, it will be noted that the bracket 57 is notched as at 66 adjacent its point of attachment to the flange 58 to accommodate an embossment 67 projecting transversely from the exterior surface of the carburetor 50. The operation of the device described in connection with Figures 7-10, inclusive, will be evident from the foregoing description, although the illustrated type of attachment does not have the flutter control such as hereinbefore described in connection with Figures 1-6, inclusive. The utility of the notch 66 adapted for various types of carburetors will be appreciated by those skilled in the art, particularly since the notch greatly increases the utility of the device without interfering with its attachment to those carburetors not having the embossment 67. Further, it will be noted that the arcuate bracket contact surface 68, which abuts the rounded exterior of the fuel-air mixture outlet portion of the carburetor, makes possible elongated contact between the bracket and the carburetor, thus increasing the stability of the assembly. This feature of the invention is particularly illustrated in Figure 11 of the drawings, and the wide adaptability of this type of bracket will be appreciated.

In the embodiment of the invention as shown in Figures 13 and 14, certain reference numerals are identical with those of Figures 1-6, inclusive, and refer to identical portions of the device. However, in this embodiment of the invention, the bracket is defined by an angularly displaced arm 70 secured to the housing 20 by suitable means, as by screw 71. The arm 70 carries a cable housing 29 secured to the bracket by screws 30 and receiving therethrough a cable housing 45 having an axially extending control rod or wire 42. The bracket 70 is provided with an upwardly projecting portion 73 having pivoted thereto an elbow arm 74, one terminal portion of which is pivotally secured to the projection 73 by suitable means, as by pivot pin or rivet 75. One terminal end of the arm 74 is apertured at 76 to receive the crank arm terminal end 19 while the other end of the arm 74 is pivoted to a spring housing 77.

As illustrated in greater detail in Figure 14, the housing 77 is provided with axial recess 78 communicating with a bore 79 slidably receiving the actuating wire 42 therethrough. A terminal block 80 is secured to the actuating wire 42 by suitable means, as by set screw 81, and the block

80 is adapted to reciprocate within the housing recess 78 against the action of a coil spring 82. A second block 83 is telescoped over the control wire 42 to abut that end of the housing 77 adjacent the cable housing 29, the block 83 being secured to the control wire 42 extending therethrough by means of a set screw 84.

The operation of this form of the invention will be readily appreciated inasmuch as actuation of the wire 42 closes the choke valve 12 as hereinbefore explained, with the resilient spring 82 accommodating flutter movement of the valve to prevent flooding of the engine with excessive fuel, in substantially the same manner as the spring 40 hereinbefore described in connection with the embodiment of Figures 1-5, inclusive, of the drawings. Upon such fluttering or venting movement of the valve 12, the housing 77 will be telescoped over the block 80 to compress the spring 82. Upon the venting of the manifold vacuum to air and the consequent feeding of a correctly proportioned fuel-air combustion mixture to the engine, the spring 82 will be effective to return the valve 12 to its closed position without disturbing the position of the actuating wire 42.

In the embodiment of the present invention illustrated in Figures 15 and 16, the choke valve 16 is mounted upon a shaft 17 as hereinbefore described, with the exception that the shaft 17 is not provided with a terminal flange. In this embodiment of the invention, the shaft 17 is hollow and a shaft terminal portion 100 projects radially outwardly beyond the air horn 11.

The device of the present invention includes a bracket 90 having a lateral flange 91 secured to a corresponding flange 92 of the carburetor by suitable means, as by screw 93. The bracket also carries an upstanding cable housing 94 adapted to receive a control cable 42 and its housing 45 as hereinbefore described, and a second upstanding flange 95 is adapted to retain an angular actuating arm 96 pivoted thereto, as at 97. One end of the arm 96 receives an actuating arm 98, which is secured to an upstanding arm 99 secured to the shaft extension 100 of the shaft 17. Since the normal shaft extension 100 initially provided for the shaft 17 terminates short of the vertical plane of the arm 96, a shaft coupling or extension collar 104 is telescoped over the free end of the extension 100. A fastening pin 103 (Figure 17) having an integral radial key 105 is inserted through the bore of the coupling 104 and the arm 99 into the interior of the hollow extension 100. The keyed pin 103 thus secures the arm 99 and extension 100 for co-rotation. A second radial key 106 on the pin 103 secures the pin and the arm 96 for co-rotation.

The actuating member 42 is secured to the angular arm 96 through a resilient flutter accommodating device such as that hereinbefore described in connection with Figure 14 and including a housing 77, a block 80 and a spring in the housing 77 (not shown).

The operation of the device of Figures 15 and 16 will be evident to those skilled in the art inasmuch as any flutter movement of the choke valve is accommodated by means of the flutter accommodating device and actuation of the manual actuation of the choke valve by manipulation of the control rod 42 may be accomplished through the arm 96.

It will be understood that modifications and variations may be effected without departing

from the scope of the novel concepts of the present invention.

I claim as my invention:

1. In a carburetor including an air horn having a pivotal choke valve therein and a crank arm connected to said valve, said arm having an outturned terminal flange, a bracket secured to said horn, an actuator arm pivoted to said bracket and supported thereby and having an aperture receiving said outturned terminal flange, said aperture and said flange being of substantially the same width, thereby to provide a positive connection between said arms, an actuator rod slidably journaled by said bracket and supported thereby, and means connecting said rod and said actuator arm including a spring supported by said bracket and yieldable when said rod is moved in a valve-closing direction and yieldable to allow movement of said valve towards its open position under influence of pressures on said valve.

2. In a carburetor including an air horn having a pivotal choke valve therewithin and a crank arm connected to said valve, said arm having an outturned terminal flange, a bracket secured to said horn, an actuator arm pivoted on said bracket and supported thereby for movement about an axis substantially aligned with the axis of said choke valve crank arm and having an aperture receiving said outturned

10 terminal flange, said aperture and said flange being of substantially the same width thereby to provide a positive connection between said arms, an actuator rod supported by said bracket and slidably journaled by said bracket, and means connecting said rod and said actuator arm including a spring supported by said bracket and yieldable when said rod is moved in a valve-closing direction and yieldable to allow movement of said valve towards its open position under influence of pressures on said valve.
